UNITED STATES PATENT OFFICE

155,118

DESIGN FOR AN ELECTRIC RANGE

Leo F. Berg, Oak Park, Ill., assignor to Hotpoint
Inc., a corporation of New York

Application March 2, 1948, Serial No. 144,879

Term of patent 14 years

(Cl. D81—4)

To all whom it may concern:

Be it known that I, Leo F. Berg, a citizen of the United States, residing at Oak Park, in the county of Cook and State of Illinois, have invented a new, original, and ornamental Design for an Electric Range, of which the following is a specification, reference being had to the accompanying drawings, forming a part thereof.

In the drawings,

Figure 1 is a perspective view of an electric range, showing my new design, the upstanding position of the backsplasher being illustrated;

Fig. 2 is an end elevational view of the electric range, similar to Fig. 1;

Fig. 3 is a perspective view of the electric range, the folded position of the backsplasher being illustrated; and

Fig. 4 is an end elevational view of the electric range, similar to Fig. 3.

The essential features of the design for an elec-

tric range disclosed reside in the foldable backsplasher having the configuration and arrangement as shown.

I claim:

The ornamental design for an electric range, substantially as shown and described.

LEO F. BERG.
